TWO-CYCLE INTERNAL COMBUSTION
ENGINE

Fritz Gossau, Berlin-Charlottenburg, Germany,
assignor to Siemens & Halske, Aktiengesell-
schaft, Siemensstadt, near Berlin, Germany, a
corporation of Germany

Application October 21, 1932, Serial No. 638,941
In Germany October 21, 1931

4 Claims. (Cl. 123—65)

My invention relates to piston cooling of internal combustion engines, and more particularly to piston cooling of two-cycle internal combustion engines.

5 When utilizing the power in internal combustion engines to the greatest possible extent, the piston heads are subjected to very high temperatures so that a special cooling of the piston parts, particularly for two-cycle internal combustion engines, becomes imperative. Cooling devices for piston heads have already been proposed. However, these devices have been generally employed in connection with two-cycle carburetor engines with a crank case scavenging pump. Such engines cannot develop a high power, since the operating mixture in this case is utilized as cooling means, and is heated to a considerable extent on passing over the hot piston head to the detriment of the weight of the cylinder charge.

20 The passage of the air through the crank case has the further disadvantage that the lubricating oil oxidizes, thus facilitating the formation of slush. This may cause a clogging of the conduits and pumps.

25 My invention has for its main object to overcome the foregoing drawbacks. To this end, the air supplied by a blower is introduced into the cylinder partly through a hollow space within the piston, closed against the crank case and in part directly into the cylinder.

My invention is illustrated in the accompanying drawings forming part of this specification, like numerals denoting like parts, in which:

30 Figs. 1 and 2 are longitudinal sectional views of a piston having at the upper part thereof a piston baffle,

Figs. 3 and 4 are longitudinal sectional views of a piston with a cambered head and,

35 Figs. 5, 6 and 7 are longitudinal sectional views showing further modified forms of the piston.

Referring to Fig. 1, the cylinder 1 has an intake 2 for the cooling and scavenging air, an outlet 3 and a flow-over passage 4 opposite to these openings. The piston 5 is provided with a cooling chamber formed by the piston head 9 and a lower transverse wall 8. This chamber separates the piston head from the crank case. The piston is further provided with an inlet port 6 and an outlet port 7 for the cooling air, both terminating in the piston chamber. In the position of piston as disclosed in Fig. 1, the intake opening 2 communicates with the flow-over passage 4 and the interior of the cylinder 1 through the piston ports 6 and 7. In this position the air flows through the piston and cylinder to the exhaust opening 3 as

shown by the arrow lines. The residual gases remain in this case in the cylinder as shown in Fig. 1 by the shaded zones 2. These residual gases are immediately above the piston and the piston head 9 and in the upper corners of the cylinder. In this case the piston head is substantially cooled from within, whereas above the piston the hot residual gases prevent at first a cooling from above. When the piston has reached the lower dead center as shown in Fig. 2, the intake 2 is opened directly into the cylinder to allow the air to freely pass into the interior of the cylinder. The air then flows directly over the outer surface of the piston head as indicated by the arrows and forces the residual gas hovering formerly above the piston head, to the upper part of the cylinder and, together with the other residual gases through the exhaust opening 3. In this manner the piston is not only cooled from the inside but also from the outside.

In the embodiment shown in Figs. 3 and 4 the exhaust opening 3 is not arranged at the same side as the intake opening 2 but at an angle of 90° to the intake opening 2. The intake 2 is made integral with the cylinder wall and bifurcated so as to form passages 10 and 11. In the position of the piston shown in Fig. 3, the cooling air entering at 2 is divided into two currents. The air flowing through the passage 10 directly into the cylinder forces the combustion gases through the exhaust opening 3 with the result that part of that air is also directed over the piston head 12, thus cooling it from above. The other current of air passes through the branch 11, the ports 6 and 7 by way of the interior of the piston and cools the head thereof from within. The air then reaches the interior of the cylinder through the flow-over passage 4, and is also used in this case to expel the combustion gases. To assist the cooling of the piston head, cooling ribs 13 are arranged on the underside thereof.

In Fig. 4 the piston 5 is shown in its lower dead center. Here the piston is only cooled from the outside, and at the same time the cylinder is charged. Upon the upward movement of the piston a further current of cooling air passes into the interior of the cylinder.

The arrangement shown in Figs. 5, 6 and 7 differs from that disclosed in Figs. 3 and 4 in that the flow-over passage establishes a communication between the intake 2 and the interior of the cylinder at first only through the piston chamber by way of ports 6 and 7 before the scavenging air is able to pass directly into the cylinder. For this purpose, as shown in Figs. 5 to 7, the branch

10 of intake port 2, (which is called the "inner terminal", because it is located nearer the inner part of the cylinder than branch 11, called the "outer terminal") is transversely in alignment 5 with the "outer" terminal of overflow passage 4.

10 In the position of the piston shown in Fig. 5 the entire cooling air flows through the intake branch 10 into the interior of the piston and cools the piston head from below. From piston port 7 10 the air passes through the outer and inner port of the flow-over passage 4 into the cylinder and forces the combustion gases into the exhaust opening 3. In the next lower position of the piston as shown in Fig. 6 part of the cooling air 15 passes directly into the interior of the cylinder through the intake branch 10, and the other part flows through the intake branch 11 into the interior of the piston and through the flow-over passage 4 into the cylinder. At that moment 20 both sides of the piston head are cooled simultaneously. When the piston has reached the lower dead center as shown in Fig. 7, the port 7 is completely closed by the cylinder wall. The cylinder is directly scavenged by the air entering 25 at 10. In the last-described arrangement the ports 6 and 7 arranged in the piston 5 and the flow-over passage 4 will again communicate with the interior of the cylinder upon the upward movement of the piston. In this case a part of 30 the charge of the cylinder may flow again through the interior of the piston which in the meantime has been sufficiently cooled down.

35 The particular advantage of the invention lies in the fact that the cooling air—flowing through the piston and being thereby intensely heated up, since it comes into contact with the piston when the latter attains the highest possible temperature—substantially serves to expel the combustion gases. In this case the volume of air 40 which is employed to expel the combustion gases may, consequently, be utilized for the cooling of the piston. That this volume of air is thereby intensely heated and expands is not of any importance with respect to the useful charge in the cylinder or to the power of the motor, since most of 45 this air leaves the cylinder again together with the combustion gases. The expansion of the scavenging air by the heat radiating from the piston rather supports the scavenging of the cylinder. 50 On the other hand, the air which is introduced into the cylinder at the lower dead center position of the piston is far less hot. It also expands to a lesser degree, and serves substantially to charge the cylinder, after the hottest portion of 55 this air has also passed into the atmosphere through the exhaust opening 3. The charge of the cylinder is, therefore, effected with colder and consequently denser air, whereas the explosion of the combustion gases is carried out by 60 means of a smaller weight of scavenging air whose volume has increased owing to the heat taken up. In this case a portion of the power required for scavenging the cylinder which has hitherto been performed by the blower is consequently accomplished by the heat radiating from the piston. The cooling air for the piston which has heretofore been in most cases sent out into the atmosphere is utilized here for scavenging the cylinder, thus effecting a saving in power, which was heretofore required for the blower.

70 The invention is especially applicable to high-speed engines, particularly to aeroengines where the highest possible efficiency is required and where now the power of the blower which was

75 heretofore necessary for the piston cooling can be reduced to a minimum.

I claim as my invention:—

1. In an internal combustion engine the combination with a crank case and a working cylinder having intake and exhaust ports in its wall and a flow-over passage in the cylinder wall located opposite to said intake port, of a working piston in said cylinder having a cooling chamber adjacent to its head closed toward the crank case, 10 said chamber having inlet and outlet ports at diametrically opposite piston sides and adapted to register respectively with said intake and said flow-over passage during the piston movement to permit scavenging air supplied to said intake to 15 reach the cylinder indirectly by way of said chamber during the outward stroke of said piston, said intake port being arranged in a position with respect to the piston path which permits scavenging air supplied to said port to enter the cylinder directly when the piston is located about its outer dead center position.

2. In an internal combustion engine in combination a crank case, a working cylinder and a working piston in said cylinder, said cylinder having an exhaust and an intake port in its wall disposed side by side in the direction of the cylinder axis, and a flow-over passage arranged in the cylinder wall diametrically opposite said intake port, said piston having a cooling chamber 30 below its head, closed against the crank case, and having an inlet and an outlet port arranged to register respectively with said intake port and said flow-over passage, during the piston movement to permit scavenging air supplied to said intake to reach the cylinder first indirectly by way of said chamber during the outward stroke of said piston, said intake port being arranged in a position with respect to the piston path which permits scavenging air supplied to said port to 35 enter the cylinder directly when the piston is located about its outer dead center position.

3. In an internal combustion engine in combination with a crank case and a working cylinder having in its wall an intake port and an exhaust port disposed circumferentially at right angles to the intake port and a flow-over passage disposed diametrically opposite said intake port, of a working piston in said cylinder, having a cooling chamber below its head, closed toward 50 the crank case, said chamber having inlet and outlet ports at diametrically opposite piston sides, and adapted to register respectively with said intake port and said flow-over passage during the piston movement, said cylinder intake port being divided in the direction of the cylinder axis into two separate branch ports to permit scavenging air supplied to said intake port to flow during the outward piston stroke into said cylinder partly directly by way of one of said branch 55 ports and partly indirectly through said chamber by way of the other branch port and said flow-over passage, for cooling both sides of the piston head, and to permit only direct flow of scavenging air into the cylinder by way of both branch ports when the piston is located about its outer dead center position.

4. In an internal combustion engine in combination with a crank case, a working cylinder having in its wall an intake port and an exhaust port 70 disposed circumferentially at right angles to the intake port and a flow-over passage disposed diametrically opposite said intake port, said intake port and said passage each having an inner and an outer port terminal located side by side in 75

the direction of the cylinder axis, the outer flow-over terminal passage being located on the same transverse cylinder level as the inner intake port terminal, a working piston in said cylinder having a cooling chamber below its head, closed toward said crank case, said chamber having an inlet and an outlet port at diametrically opposite piston sides adapted to register respectively with said intake port and said flow-over port terminals during the piston movement, whereby

5 during the outward piston stroke scavenging air, supplied to said intake port terminals, flows into said cylinder first only indirectly by way of said cooling chamber, then partly indirectly by way of said chamber and partly directly by way of the inner intake terminal, and whereby the scavenging air flows into the cylinder only directly by way of the inner intake terminal when the piston is located about its dead center position.
